(57) **CLAIM**

The ornamental design for a truck storage system, as shown and described.

DESCRIPTION

The present application claims priority to U.S. patent application Ser. No. 13/932,600, filed on Jul. 1, 2013, which is expressly incorporated herein in its entirety by reference thereto.

FIG. 1 is a rear perspective view of an ornamental design of a first exemplary embodiment of a truck storage system showing my new design;

FIG. 2 is a top view thereof;

FIG. 3 is a rear view thereof;

FIG. 4 is a front view thereof;

FIG. 5 is a bottom view thereof;

FIG. 6 is a right side view thereof;

FIG. 7 is a left side view thereof;

FIG. 8 is a rear perspective view of an ornamental design of a second exemplary embodiment of a truck storage system showing my new design;

FIG. 9 is a top view thereof;

FIG. 10 is a rear view thereof;

FIG. 11 is a front view thereof;

FIG. 12 is a left side view thereof;

FIG. 13 is a right side view thereof; and,

FIG. 14 is a bottom view thereof.

Mirror images of FIGS. 8 to 14 show corresponding views of an ornamental design of a third exemplary embodiment of a truck storage system showing my new design, the mirror image of FIG. 12 showing a right side view thereof, and the mirror image of FIG. 13 showing a left side view thereof.

The broken line showing of the Figures is for purposes of illustration and forms no part of the claimed design.
